UNITED STATES PATENT OFFICE

LAMBERT L. RAYMOND, OF MINNEAPOLIS, MINNESOTA, ASSIGNOR TO BRODERICK-SON-RAYMOND CO., OF MINNEAPOLIS, MINNESOTA, A CORPORATION OF MINNESOTA

LAMP WITH MARKINGS

Original application filed January 25, 1926, Serial No. 83,806. Divided and this application filed June 3, 1927. Serial No. 196,295.

This invention relates to a Christmas tree decoration, and particularly to a novel combination of reflector and lamp. It is now the common practice to decorate Christmas trees and similar objects with small electric lamps, which lamps are often of various colors. It is also now common practice to use reflectors of various ornamental shapes with such lamps. While such reflectors and lamps have been used, the lamps of the prior art have been of uniform color or have had all parts thereof of uniform degree of light permeability.

It is an object of the invention to provide a lamp having thereon portions of different degrees of light permeability and of various formations.

It is another object of the invention to provide a Christmas tree electric lamp having a bulb and plug, said bulb being colored and translucent for the greater part of its area, but having a portion adjacent the plug which is clear.

These and other objects and advantages of the invention will be fully set forth in the following description made in connection with the accompanying drawings in which like reference characters refer to the same parts throughout the different views, and in which,

Fig. 1 is a view in front elevation of a reflector and lamp;

Fig. 2 is a horizontal section taken on the line 2—2 of Fig. 1, as indicated by the arrows;

Fig. 3 is a view in front elevation of a modified form of reflector and lamp;

Fig. 4 is a horizontal section taken on the line 4—4 of Fig. 3, as indicated by the arrows;

Fig. 5 is a view in front elevation of a reflector and lamp of further modified form;

Fig. 6 is a horizontal section taken on the line 6—6 of Fig. 5, as indicated by the arrows.

Referring to the drawings, in Fig. 1 is shown a reflector 10 made of sheet material, preferably metal, the same having a shape, in front elevation, of a five-pointed star. The reflector 10 is curved toward the front, as seen in the drawings, the curvature being

uniform with the central axis extending normal to the reflector at the center thereof. The reflector 10 has its surface formed with a multiplicity of small substantially semi-spherical depressions 10a. The surface of the reflector, including the depressions 10a, is quite highly polished so as to give a high degree of reflection. While these depressions may be disposed in various ways and arrangements, in the embodiment of the invention illustrated, they are shown as being arranged in rows parallel to the sides of the star forming the reflector. The reflector 10 has a central aperture therein and a bushing or washer 11 of insulating material is provided having a central aperture considerably smaller than the aperture in the reflector, said washer 11 being placed against the rear side of the reflector with its central axis co-axial with the central axis of the reflector. Said washer 11 is secured to the reflector by a plurality of circumferentially spaced and preferably pointed tangs 10c extending through washer 11 and bent over on the outer side thereof in a manner similar to that shown in Fig. 4. A lamp 12 is provided having the bulb portion 12a of glass, or similar transparent material, and the rear part comprising the threaded sleeve 12b and the tip contact 12c insulated from said sleeve. The lamp 12, preferably, is provided with some coating or color, as indicated by the shading. Any particular color may be used. The lamp 12 is provided with a portion 12d, and while this portion may be of various shapes and variously arranged, in the embodiment of the invention illustrated, it is shown as a zigzag band extending circumferentially about the bulb 12a substantially at the widest portion thereof. The band 12d thus has a plurality of pointed portions 12e, and these are arranged with their central axes in alinement with or directly in front of the central lines of the respective points of the reflector 10. It may be stated that the portion or band 12d is of different color or degree of light permeability than the remainder of the bulb 12a and while various degrees of light permeability may be used, as many different colors,

in the embodiment of the invention illus- 100

trated, the band 12d is shown as being clear.

In operation, the reflector and lamp disclosed will be mounted on a Christmas tree, or other Christmas decoration, in the usual manner, by screwing the sleeve 12b of the lamp into the customary lamp socket, the reflector 10 being clamped or held between the lamp and lamp socket. When the lamp 12 is illuminated, the color in the main portion 10a of the bulb will be reflected from the surface of the reflector 10 so that said reflector will show the color from the bulb in the shaded portion 10b. The band 12d, however, will cause the surface of reflector 10 to show a different reflection about the border of the same, as indicated by the unshaded portion in Fig. 1, thus forming two zones of different reflecting effect on the reflector. If the band 12d is clear, this portion of the reflector will show with a very high light. If the band 12d is of a different color, this color will be reflected about the edge of the reflector 10. A very striking and beautiful effect is thus obtained on the surface of the reflector 10. The pointed portions 12e as stated are circumferentially aligned with the points or zones of the reflector so that the border of said reflector is bright, as shown by the unshaded portion in Fig. 1.

In Figs. 3 and 4, a different form of reflector 15 is shown having a plurality of radially extending points 15e. The surface of reflector 15 is also highly polished and provided with a multiplicity of substantially semi-spherical depressions 15a, such as shown in the drawing. Reflector 15 is also curved forwardly uniformly about a central axis and is provided with a central aperture 15b. A washer or bushing 16 of insulating material engages the rear of reflector 15 and is held thereon by a plurality of circumferentially spaced tangs 15c passing therethrough in the same manner as already described for washer 11 in reflector 10. A lamp 17 is provided having the bulb portion 17a which is coated, or otherwise colored having the threaded sleeve 17d insulated from the tip contact 17c. The bulb 17a is provided with a portion 17b of a different degree of light permeability from the remainder of the bulb and while this portion may be of various shapes and arrangement, in the embodiment of the invention illustrated, it is shown as a circular band. The portion 17b may be either of a different color or may be clear.

When the reflector 15 and lamp 17 are assembled on a Christmas tree or other similar device, as already described for lamp 12 and reflector 10, the color on the main portion of bulb 17 will be reflected from the central part of the reflector, as indicated by the shading 15d in Fig. 3. The band 17b, however, will emit light of a different coloring or intensity which will cause a different reflection from the outer ends of the points 15a, as indicated

by the unshaded portions in Fig. 3, thus giving zones of different reflecting effect. If the band 17b be clear, this latter portion will show quite bright and if the band 17b be of a different color, this color will be reflected from the portion outward of the portion 15d. A beautiful and striking effect is thus produced.

In Fig. 5, another form of reflector 20 is shown having its periphery formed with a plurality of semi-circular lobes 20a. The surface of the reflector 20 is also highly polished and provided with a multiplicity of small semi-spherical depressions 20b similar to the depressions 10a. While the depressions 20b may be variously arranged, in the embodiment of the invention illustrated, they are shown as disposed in a double row about the outer edge of the reflector 20 and also extending inwardly in radial lines in double rows. Reflector 20 is also provided with a washer 21 extending across the central aperture in reflector 20 secured thereto in a manner already described for washers 11 and 16. A lamp 22 is provided having the usual bulb portion 22a, the rear sleeve portion 22b insulated from the tip contact 22c. The bulb 22a will be coated or otherwise colored and the same is shown as having circumferentially spaced portions 22d of a different degree of light permeability than the remainder of the bulb. While the portions 22b may be variously arranged, in the embodiment of the invention illustrated, they are shown as extending radially and outwardly toward the pointed end of the lamp bulb. Portions 22d may be either clear, or of a different color from the remainder of the bulb.

In operation, when the reflector 20 and lamp 22 are assembled and held, as above described, and the lamp illuminated, the color on the main portion of the bulb will be reflected from the reflector 20, as indicated by the shaded portions in Fig. 5. The portions 22d, however, will cause portions or zones of a different reflective effect on reflector 20. The portions 22d will be disposed with their central lines in alignment with the radial line extending between the lobes 20a, at each side of which latter lines the rows of depressions 20b are disposed. The radial rows of depressions 20b will, therefore, be illuminated by the light issuing from the portions 22d, and if the portions 22d be clear, these radial rows will be highly illuminated and a very bright reflecting effect secured. If the portions 22d be of a different color from the remainder of the bulb, this color will be reflected along the radial rows, as indicated by the unshaded portions of Fig. 5. A very handsome and striking effect is thus produced.

The reflector illustrated is substantially the same as that disclosed and claimed in appli-

cant's U. S. Patent No. 1,617,221 issued Feb. 8th, 1927.

From the above description it is seen that applicant has provided a novel and efficient 5 electric lamp for Christmas trees and one which will give new, important and pleasing results. The portions of the lamp which emit different kinds or colors of light will produce 10 different effects on the various reflectors which may be used therewith, which effects will be very pleasing, beautiful and highly ornamental. It is also pointed out that when the lights are used without reflectors as is common on Christmas trees, the light will 15 shine through the clear portion and will illuminate other objects on the tree. With the structure shown in Fig. 6 the objects in the rear of the lamp and in the rear part of the tree will be illuminated, as trees are often 20 placed in corners of a room, the rear of the tree tends to be dark. With such lamps as disclosed this part of the tree will be illuminated and beams of light will shine thereinto giving a very pleasing and ornamental effect. It 25 is also pointed out that by having a clear portion on the bulb more radiation of heat is obtained. As is well known, Christmas tree lamps get quite hot due to the translucent coating used to get the color thereon.

30 It will, of course, be understood that various changes may be made in the form, details, arrangement and proportions of the parts without departing from the scope of the invention, which, generally stated, consists in 35 the novel parts and combinations of parts disclosed and defined in the appended claims.

This application is a division of applicant's co-pending application for Christmas tree reflector and lamp, Serial No. 83,606, filed 40 January 25, 1926, allowed March 5, 1927, which application has since the filing of this application matured into U. S. Letters Patent No. 1,632,850 issued on June 21, 1927.

What is claimed is:

45 1. A Christmas tree lamp bulb having the greater portion of its surface of one color and translucent and having a zone of clear glass extending about said bulb in a zigzag line.

50 2. A miniature electric lamp comprising a bulb and a plug to which said bulb is attached, said bulb having a body portion extending from said plug to its outer end, said body having the greater and outwardly disposed portion of its area colored and translucent, said body having a smaller clear portion adjacent said plug extending circumferentially of said body, whereby light can shine through said clear portion and produce a high reflecting 55 effect on a reflector.

In testimony whereof I affix my signature.
LAMBERT L. RAYMOND.
